UNITED STATES PATENT OFFICE.

WILLIAM H. SCHUERMAN, OF NASHVILLE, TENNESSEE, ASSIGNOR TO LEONORA B. SCHUERMAN, OF NASHVILLE, TENNESSEE.

ADDING MACHINE.

Application filed May 2, 1922. Serial No. 557,899.

To all whom it may concern:

Be it known that I, WILLIAM H. SCHUERMAN, a citizen of the United States, residing at Nashville, in the county of Davidson and State of Tennessee, have invented certain new and useful Improvements in Adding Machines, of which the following is a specification.

This application is a continuation in part 10 of my application, Serial #421,772, filed November 4th, 1920. The present invention has for an object to provide a simplified form of adding machine with novel mechanical features having value for application 15 in various ways other than the particular embodiment herein shown. It is a special purpose of the invention to provide a machine of this character operable by a key-board adapted to be manipulated by one 20 hand of an operator, leaving the other hand free for manipulation of checks or other memoranda, and without requiring the movement of the hand from a convenient position over the key-board, manipulation 25 of the keys being possible by digital movement principally.

It is an especially important aim of the invention to provide a novel mechanism by which the number of keys required to 30 operate such a device may be materially reduced. A further purpose is to provide an improved and efficient means whereby consecutive operation of any number keys in the setting down of an item will result in 35 the accumulation of the sum involved in each key operation successively on the unit, tens, hundreds and other wheels to the left, respectively. A further aim of the invention is to provide a mechanism of this kind which 40 may be embodied in a very compact form adapted to be produced at a low cost, and which will be efficient and durable, and liable in a minimum degree to casual displacement of the parts operatively, or otherwise than 45 by normal operation of the machine.

The invention involves also additional objects, advantages and features of invention in the construction, arrangement and combination of parts, as may be understood 50 from the following description and accompanying drawings of one embodiment of the invention, wherein,

Figure 1 is a top view of the mechanism with the casing and framing parts omitted, 55 Fig. 2 is an end elevation of the mecha-

nism with the casing and shafts in section on the line A—B of Fig. 1.

Fig. 3 is an elevational view of one of the number keys and the connection whereby two different numbers may be registered by 60 the same key,

Fig. 4 is a view of the mechanism for operating the tripping shaft.

Figure 4^a is a detail of the lever 44, detached.

Figs. 5 and 6 are two views of the registering or accumulating mechanisms.

Fig. 7 is a detail of the tripper shaft,

Fig. 8 is a detail of the blank for the ratchets 60 of Figs. 5 and 6.

Fig. 9 is a detail of the lever operating this ratchet.

This invention involves the use of a series of register or number wheels, and a key-board with means whereby when the first 75 key is operated for the recording of an item, the figure involved by the operation of such a key will be registered on the unit wheel, while the amount involved by the operation of the second key, or a repeated operation 80 of the first key used, will be recorded on the wheel in the tens column, the next key operation registering on the hundreds wheel, and so on. Associated with the wheels there is 85 means whereby when a previous item has been recorded an additional sum added on a wheel aggregating ten for that column will be carried forward to the next wheel properly, or accumulated, as required in such machines. Also, means is provided where-

90 by two numbers different by five units may be recorded selectively or alternatively, by each key, so that only five numbered keys are required in the machine, which are so positioned that they may be ordinarily operated by the four digits of the left hand, a shift key being provided operable by the thumb of that hand to cause the recording of one such of the numbers represented on the keys. The machine includes five number keys, of which four operate register-accumulating wheels, these being designated, 95 1—6, 2—7, 3—8, 4—9, respectively being utilized to register the numbers by which they are designated, the fifth key being 100 designated 0—5. It has no connection with register wheels and while it may be operated when such characters are involved, other mechanism operated in association with the key act when necessary to operate the 105

110

register wheel or wheels. The last mentioned mechanism includes the shift key S which must be depressed when the higher characters on any of the keys are to be registered. The keyboard also includes a release key N, which is operated after the entry of each item.

In the present instance, no clearing device is shown, and to return the number wheels to initial position, these may be operated manually or any suitable clearing mechanism incorporated upon the device.

The key-board is located over a horizontal forward extension of a casing 1, by which the complete mechanism is enclosed, this casing having a series of view openings 2 through which number wheels 3 may be viewed, mounted immediately thereadjacent. The keys are arranged so as to accommodate themselves to the natural positions of the fingers of one hand when placed over the key-board. The keys are carried upon vertical stems 4, pivoted at 5 upon lower stabilizing links 7, which are pivoted upon a fixed shaft 9 adjacent the lower part of the casing and rearwardly of the stems. Vertically above and parallel to the shaft 9, there is a larger shaft 8, fixed in the casing from which operating levers extend to the stems and also rearwardly for engagement with parts to be moved. From the first mentioned four number keys, levers 6 are so extended, and from the key 0-5, a lever 6' extends, while from the keys S and N, levers 6^a and 6^b respectively are extended rearwardly, pivoted like the others upon the shaft 8. The lever 6^a adjacent the rear part of the casing is engaged by a spring 19 attached to the bottom of the casing, to hold it yieldingly at initial position, and upwardly from its rear end there is extended a link 10, connected pivotally to a lifter arm 11, which is pivoted upon a horizontal stationary shaft 12 in the upper part of the casing, the arm extending rearwardly and engaging under one end of a bar 13 fixed upon links 14-14' pivoted on the shaft 12 so that the bar may reciprocate between the position shown in Fig. 2, and the position dotted in Fig. 3. A spring 21 on the shaft 12 is utilized to hold the bar 13 yieldingly at the lower limit of movement. There is suspended from the bar 13 an arm 15, having the notch 16 in its forward side adapted to receive a counter bar 17 for support of the bar 13 in its elevated position at times. A spring 18 is mounted on the shaft 13, engaging the arm 15 to bear it forward yieldingly against the shaft 17. The arm 11 is formed with an inclined rear edge, arranged to engage a pin 20 projected from the side of the arm 15, toward the same rearwardly as the arm 11 is lowered, and thus disengage the notch 16 from the shaft 17, which will permit the shaft 13 to fall to its initial posi-

tion. Upon the shaft 12 immediately adjacent the arm 14 at one side of the casing, there is revolvably mounted a gear 30 having forty teeth, and upon the arm 14^a and pivoted like the links 14-14', adjacent the end of the bar 13 there is mounted a ratchet 29 engaging the gear to rotate the same when the arm 14^a is raised, and it will ride upon the gear when the arm is lowered. It should be noted that the movement of the ratchet produced by the lever 6^a upon operation of the key S is such that the gear 30 will be moved over an arc including five teeth.

It may also be noted that the shaft 17 does not project over the lever 6^a. The bar 17 is initially supported upon arms 26 operated by the levers 6, as will be explained. The rear ends of these arms rest initially upon a stationary shaft 24. Each lever 6 is connected by a short link 22 to a lever 23 pivoted upon and extending forwardly from the shaft 24, and from an intermediate position on the lever 23, a link 25 is extended upwardly and connected to a respective arm 26. The link 22, lever 23 and arm 26 are the same for all four keys, but the links 25 and the position of the pins by which they are connected with the arms 23 and 26 vary with the keys involved. The adjustment is such that the angle of arc through which the counter bar 17 is moved with respect to the shaft 12 varies for the keys 1-6, 2-7, 3-8, and 4-9, in the ratio 1, 2, 3, and 4. It should also be noted that raising of any of the arms 26 will lift the bar 17, and by reason of the links 14-14' resting on this bar, the bar 13 will also be raised, causing operation of the gear 30 to an extent corresponding to the value of the key operated to produce such movement. The movement of the gear 30 produced by the operation of the key S will have a value of 5 in the group of values named. In other words, operation of the key 1-6, will move the gear 30 the distance of one tooth and the operation of the key 4-9 will move that gear the distance of four teeth. In case the key S is operated in conjunction with the key 4-9, the gear 30 will be rotated a distance of nine teeth, first, five teeth by the key S and then four teeth more by the key 4-9. Due allowance may, of course, be made for lost motion in operative parts.

A shaft 32 is mounted revolvably in the casing forwardly of and slightly above the shaft 12, and fixed upon this shaft there are gears 31, one for each wheel 3, the first or right hand gear 31 being meshed with the gear 30 before mentioned so that all are turned when any of the keys named are operated. Pivoted for free movement on the shaft 32 adjacent each gear 31 there is a lever 35, having a pin 34 set adjacent its outer end upon which there is revolvably a gear 33 meshed with the gear 31. Each of

the levers 35 is formed with an inwardly extending arm to which there is connected a spring 37 by which the forward end is held yieldingly in raised position, the 5 springs being engaged on the shaft 8. At the side of and fixed with respect to each wheel 3, there is a ten-toothed gear 39 and the levers 35 swing in such an arc that the gears 33 thereon will readily engage respective 10 five gears 39 at one limit of swinging movement.

All except one of the levers 35 are in inoperative position, and their successive movement into operative relation is attained 15 by means of a tripping shaft 36 having ten pins or teeth 38 thereon and arranged spirally therearound each pin being located on a radius at an angle of 36 degrees to the radius of the next adjacent pin, or one tenth 20 of a circumference. This arrangement and number of pins, has no relation to the number of teeth on the gears, but the number of pins may correspond to the number of register wheels, according to the maximum 25 sum which may be set. The rear ends of the levers 35 are notched, so as to form bills positioned to engage respective teeth on the tripper shaft, as at 49, the levers being so shaped that as one tooth passes out 30 of engagement with one, the adjacent tooth to the left will operate the respective lever 35 to bring the gear 33 into mesh with the gear 39 of the counter wheel. To the left hand end of the tripper shaft 36, there is fixed 35 a gear 48 the number of teeth on which should equal or be a multiple of the number of pins or teeth on the trip shaft, and meshed with the gear 48 there is a large gear 47 revoluble on the shaft 12 having 40 a multiple relation to the gear 48. In the present instance, the gears 48 and 47 have ten and forty teeth respectively.

The trip shaft 36 is to be rotated a distance of one pin or tooth thereon for each consecutive operation of number keys. For 45 this purpose, a shaft 41 is mounted in arms 42 pivoted upon the shaft 8, to rest upon the levers 6 and 6', and from an intermediate position on the arms 42 a link 43 is 50 extended upwardly to the forwardly projected arm of a lever 44 pivoted on the shaft 12 beside the gear 47, and extending rearwardly thereof. A ratchet 45 is mounted on the rear end of the lever 44 engaging the teeth of the gear 47 to rotate 55 the gear under upward movement of the rear end of the lever 44. Upward movement of the rear part of any of the levers 6 and 6' will thus raise the shaft 41, operating the lever 44 and moving the gear 47 which drives the trip shaft. The shaft 41 and the connections of the links 43 are so positioned that the movement imparted to the shaft 36 will disengage one tooth 38 60 from a lever 35, and cause the next tooth

to the left to operate the respective lever 35 whereby the wheels 3 will be operated as required in succession to the left on consecutive operations of numbered keys. In the present instance, movement of one tooth 70 on the gear 47 only is required.

For the reason that in setting the items of a series to be added, it is necessary to start with the right hand figure in each item and the gear 33 at the right hand side of 75 my machine must be in mesh when beginning each item. Means is provided to return the shaft 36 to its initial position after setting of each item, this means being operated by the key N. The lever 6^b of this 80 key is extended rearwardly from the shaft 8 beneath the shaft 41 and a distance beyond, where a link 50 is extended upwardly therefrom to an arm 51 pivoted upon the shaft 12 and carrying a ratchet 52, adapted 85 to engage one of four pins 53 equally spaced circumferentially of the gear 47 and projecting laterally therefrom. The throw of the arm 51 under operation of the lever 50 is such that at the termination of its movement in engagement with any one of the pins, the shaft 36 will have been rotated to such point that its next operation by the lever 44 will cause operative positioning of the first gear 33. As the lever 44 is operated at the same time by the lever 6^b, the return movement of the lever 6^b will cause the further movement of the shaft 36 to bring the first set of gears into mesh.

While various carrying means may be 100 found applicable to my machine, in the present instance, the means whereby one turn of one wheel will add one to the number registered on the next wheel to the left comprises the following:—

Upon each wheel at a suitable location a projection, pin, or tooth 54 is provided adapted to engage the block or other projection 55 upon a lever 56 (one adjacent each wheel) pivoted freely upon the shaft 110 8 and extending upwardly so as to rest against the forward side of the shaft 40, being so held by means of a spring 57 mounted on the shaft 8. A short arm 60 is freely pivoted upon the shaft 40 adjacent 115 the gear 39, having a leaf spring 61 secured thereon serving as a ratchet and engaging the teeth of the gear 39 so as to rotate the gear in a clockwise direction when the arm 60 is oscillated. The arm has a pin 59 projected laterally outward therefrom engaging in a slot 58 adjacent the outer end of the arm 56, so that when the tooth 54 of one wheel engages the block 55 the arm 60 will be swung so as to rotate the next wheel 3 120 one number.

The various ratchets may be spring-pressed in customary practice, and in order to prevent reverse movement of gears, pawl or keeper devices may be employed as found 125 130

desirable. For retaining the gears 39 against casual movement, and to hold the wheel 3 in proper position, an angle plate 63 is mounted upon the front of the case 1, having suitable slots receiving the forward parts of the wheels with sufficient snugness, and provided with springs 64 projected so that their inner ends engage between the teeth of the gears 39 to hold the wheels in positions with numbers registered with the openings 2; yieldingly for rotation in one direction, and positively against rotation in the opposite direction. A pawl 65 is pivoted upon the shaft 8 and swung to engage one of the gears 31 preventing reverse movement of any of those gears. A similar pawl 66 mounted on the shaft 8 engages the gear 48 to prevent backward movement of the tripper shaft.

20 In the position of the parts shown in Fig. 1, the mechanism is represented as having been operated to set the item of \$1,116,350.47 these being the numbers adjacent the left hand side of the sheet, in position where they would be viewed through the opening 2 of the case. In order, now, to add the item \$736.14 to this number, the key N having been last operated to set the gear 33 in the first set in operative position, the operator would first depress the key 4-9 and the lever 6 of the key operated would lift the corresponding arm 26 such distance, that the shafts 17 and 13 would be raised such distance that the ratchet 29 would rotate the gear 30 four teeth, this motion being so transmitted that the number 4 would be registered on the wheel 3 at the right. In this operation the shaft 41 would also be lifted, causing operation of the lever 44, so that upon return movement of the parts, the lever 44 would rotate the gear 47 moving the trip shaft 36 so that the first lever 35 would be disengaged and the second moved to operative position. Thus, if the same key or any other were next operated, it would be the second number wheel which would be operated. Next, the key 1-6 is pressed down, which results in rotating the second number wheel from zero to "1," and also lowers the third lever 35 to operative position. The operator then depresses the key S and holding this, operates the key 1-6. Operation of the key S through the lever 6^a, link 10 and arm 11 raises the shaft 13 and the arm 14 causing the ratchet 29 to move the gear 30 five teeth; the pendent arm 15 then receiving the shaft 17, in its notch 16, whereby the parts are fixed with respect to the shaft 17 in the position they will move, the shaft 13 and associated parts, however, being free for movement beyond this lever without obstruction. When the operator then operates the key 1-6 as mentioned, the lever 6 of that key 65 operating the arm 26, raises the shaft 17 a

distance, the motion being transmitted through the arm 15 to the shaft 13 and arm 14, whereby the ratchet 29 moves the gear 30 a further distance of one tooth, the result of these operations being the registration of the number 6 on the third wheel from the right. Next the key 3-8 is operated and then the shift key S is held downward while the key 2-7 is depressed. This completes the addition of the number assumed. The key N is then depressed and released, which returns the shaft 36 to its initial position in the manner before described. Additional items of various orders may be then added in the same manner.

The mechanism described may be associated with additional mechanism as found desirable, or combined with other familiar forms of adding appliances.

What is claimed is:—

1. In a machine of the character described, a plurality of number wheels revoluble in parallel planes a shaft having respective swinging arms thereon, a revoluble shaft parallel to the first shaft and having respective projections thereon to successively engage the arms for movement of the arms toward the number wheels, yielding means tending to hold the arms in inoperative position, a key-board, operative means between the keys and number wheels including separable members one for each wheel carried upon the respective swinging arms thereadjacent, and means operable by each key on full movement to rotate the second named shaft.

2. In an adding machine a keyboard comprising keys, each for two numbers, movable lift arms, certain keys connected to respective arms for movement thereof in proportion to the value of the respective keys, a cross bar movable by said arms and tending to rest thereagainst, a number wheel, operative means therefor including an element resting upon said bar, an auxiliary key and connections to move the number wheel independently of the said bar, a notched arm carried by the auxiliary connections to receive the bar in the notch after predetermined movement, and movable for further actuation of the number wheel by movement of the bar, the machine including means to release the arm from the bar under movement to initial position.

3. In an adding machine, a number key, a lever operatively connected thereto, a shiftable element thereover, a connection between the shiftable element and the lever for a predetermined movement of the shiftable element upon operation of the key; a second shiftable element means whereby the second shiftable element will be moved by the first shiftable element; means including an auxiliary key to move the second shiftable element independently of the first shift-

able element to a predetermined advanced position, means to fix the two shiftable elements in the last named relation to each other for further movement as a unit on 5 operation of said lever, and a number registering device operatively connected with the second shiftable element for the purposes described.

4. In a machine of the character described, 10 a plurality of number registering wheels, having gear teeth, a corresponding number of operating devices therefor including swinging arms having gears at their outer ends to mesh with the teeth of the wheels 15 at one position and being normally in inoperative position yieldable for movement to operative position, rotating means having parts located to successively move the arms to operative position, a keyboard having 20 keys operatively connected with all the gears on said arms, and means constructed to operate said rotating means step by step under operation of the keys, for the purpose indicated.

5. In a device of the character described, 25 a number registering device including a shaft having a ratchet thereon, a swinging arm on the shaft having a pawl to move the ratchet, an auxiliary key to move the arm a distance predetermined, a second 30 swinging arm, means carried thereby forming a rest for the first arm in one position, a means to form a supporting connection between the arms when the first named arm has been moved by the auxiliary key, means 35 to move the supporting connection to inoperative position by return movement of the auxiliary key, a number key, and operative connections between the number key and the second named arm for movement proportionate to the number. 40

In testimony whereof I have affixed my signature in presence of two witnesses.

WILLIAM H. SCHUERMAN.
